W. Smith

of 1 - Design of Water Closet Receiver.

No. 3060 PATENTED

MAY 26 1868

United States Patent Office.

WILLIAM SMITH, OF SAN FRANCISCO, CALIFORNIA.

Design No. 3,060, dated May 26, 1868.

DESIGN FOR A WATER-CLOSET RECEIVER.

The Schedule referred to in these Letters Patent and making part of the same.

TO ALL WHOM IT MAY CONCERN:

Be it known that I, WILLIAM SMITH, of the city and county of San Francisco, and State of California, have originated a new Design for Water-Closet Receiver, of which the following is a full, clear, and exact description, reference being had to the accompanying drawings making part of this specification.

My invention is represented by a perspective view.

In the drawings, A represents the body of the device, formed in two parts, which are adapted to be united along the joints $a' a'$; B is the flange or rim around its top; C, the bottom plate; D, the flange, where the sections, of which it is formed, are united; E, the opening for the water-pipe; and F, a bulge of considerable size upon one side of the device, corresponding to a recess or side chamber of similar form within.

The walls of the water-closet receiver are formed as shown in the drawing, having a graceful curve, $a a a$, from the rim B to the bottom plate C, and being contracted to comparatively narrow limits at their lower end.

Having thus described my invention, what I claim as new, and desire to secure by Letters Patent, is—
The design for a water-closet receiver, substantially as above set forth and shown.

The above specification of my invention signed by me, this ninth day of March, 1868.
